UNITED STATES PATENT OFFICE.

CHARLES OSBORNE, OF NORTH ATTLEBOROUGH, MASS., ASSIGNOR TO THE WHITING MANUFACTURING COMPANY, OF NEW YORK CITY.

DESIGN FOR HANDLES FOR SPOONS AND FORKS.

Specification forming part of Design No. 7,909, dated December 1, 1874; application filed June 20, 1874.
[Term of Patent 14 years.]

CASE A.

To all whom it may concern:

Be it known that I, CHARLES OSBORNE, of North Attleborough, Bristol county, in the State of Massachusetts, have invented a new and original Design for the Handles of Spoons and Forks, of which the following is a specification:

The accompanying drawings form a part of this specification.

Figure 1 is a view of the upper side or front of the handle, and Fig. 2 a view of the under or reverse side.

Similar letters indicate corresponding parts.

The handle is composed, as usual, of two principal sections—finger-piece A and shank B. The lower end of the finger-piece is tapered and the upper end elliptical, and the whole bordered with a double bead, *a b*, the outermost of which, marked *a*, is a jointed reed, and the innermost of which, marked *b*, is plain. The field within bears slightly curved stems *c* with pointed leaves *d* and tufts, composed of slender radiating filaments *e*. On one of the stems is a bird rousant, *f*. Toward the junction with the shank is a series of light interwoven diagonal bands, *g*. Below this, marking the junction with the shank, is a stout encircling band, *h*, corded, as shown. The reeded decoration of the edges is continued along the shank. The center of the

shank bears a heavy reed, *m*, correspondingly jointed. Near the lower end of the shank are corded crossed bands *i j*. The ends of the central reed *m* are shown as cut obliquely.

The pattern or design may be varied in size, and in the precise arrangement of the stems and other details, so long as they form essentially the same design, and produce the same ornamental and distinctive effect. Both the faces may be alike, or but slightly varied, but I propose in most instances to thus decorate only the face, and make the reverse side plain.

I claim as my invention in designs for spoon and fork handles—

1. The jointed bead or reed *a* in the margin and the corresponding jointed reed *m* along the center line, with the bands *h i j*, as shown and described.

2. The design for a spoon or fork handle, having the jointed reeds *a m*, bands *h i j*, lighter interwoven bands *g*, and with a bird, stems, and tufts, as shown and described.

In testimony whereof I have hereunto set my hand this 18th day of June, 1874, in the presence of two subscribing witnesses.

CHARLES OSBORNE.
